UNITED STATES PATENT OFFICE.

JOHN H. MURCH, OF SAN FRANCISCO, CALIFORNIA, ASSIGNOR TO AMERICAN CAN COMPANY, OF SAN FRANCISCO, CALIFORNIA, A CORPORATION OF NEW JERSEY.

AUTOMATIC DIE-GRINDER.

1,326,462.

Specification of Letters Patent.

Patented Dec. 30, 1919.

Application filed March 8, 1917. Serial No. 153,341.

To all whom it may concern:

Be it known that I, JOHN H. MURCH, a citizen of the United States, residing at the city and county of San Francisco and State 5 of California, have invented certain new and useful Improvements in Automatic Die-Grinders, of which the following is a specification.

The present invention relates to grinding 10 machines, and more particularly to a machine for automatically grinding the annular dies used in can-making machinery for the stamping of can end blanks.

The object of the invention is to provide 15 a machine for the described purpose, by means of which an annular die may be automatically ground to the desired form, and in which the grinding means are mounted for universal adjustment relative 20 to the die holding means.

In order to comprehend the invention, reference should be had to the accompanying sheets of drawings, in which:—

Figure 1 is a partly broken perspective 25 view of the machine embodying my invention.

Fig. 2, is a detailed transverse section taken, in the direction of the arrows, in a plane represented by the line 2—2 of Fig. 1;

Fig. 3, is a section taken in the direction of the arrows in a plane represented by the line 3—3 of Fig. 1;

Fig. 4, is a vertical section taken in the direction of the arrows in a plane represented 35 by the line 4—4 of Fig. 3, showing the grinding wheel holder elevated to its inoperative position.

In the drawings, the reference numeral 1 designates a suitably constructed base, upon 40 which is mounted a horizontal bed-plate or table 2. Rising from the table 2, at the rear corners thereof, are vertically disposed brackets 3 and 4, Figs. 1 and 4 of the drawings. A transverse member 5 is pivotally 45 connected at one end with the bracket 3, at 3' and is adapted to be removably secured, as by means of a bolt 4', Fig. 1, at its other end to the bracket 4. Said transverse member thus forms normally a bridge across 50 the upper ends of the two vertical brackets 3 and 4, and may be elevated to the position shown in Fig. 4 of the drawings.

The transverse member 5 carries the grinding head. This head comprises a block 6, Figs. 1, 2 and 3 of the drawings,

which is secured to the transverse member 5 for lineal sliding movement, by means of a clamping yoke 7. The latter has a lug 8 projecting from its inner surface and lying within the channel portion of the transverse member 5. A lineally disposed screw 9, Figs. 2, 3 and 4 of the drawings, is rotatably carried at 10, Fig. 4, of the drawings, in the end of the transverse member 5, and is screwed through the lug 8 carried by the 60 yoke 7 of the grinding head, so that by the rotation of said screw 9, said head may be moved lineally with respect to the transverse member 5. A hand wheel 11 is provided at the outer end of the screw 9 for 65 the operation thereof.

The member 6 of the grinding head is provided with vertically disposed guide-ways 12, Figs. 1, 2 and 3 of the drawings, and within said guide-ways is carried a vertically 75 slideable block 13. Said block 13 has a rearwardly projecting lug 14, Fig. 2, which is internally threaded, and through which passes a vertically disposed screw 15, said screw being rotatably carried, at 16, in 80 the upper portion of the head member 6, and being provided with a hand-wheel 17. Thus by the operation of said hand wheel the block 13 may be moved vertically with respect to the head member 6. 85

The block 13 carries a forwardly projecting bracket 18, Figs. 1, 2 and 3 of the drawings, in which is journaled the grinder spindle 19. Said spindle carries a grinder wheel 20 on its forward end, and a pulley 21 on its rear end. A belt 22, Figs. 1, 3 and 4, passes over said pulley 21 and transmits power to the grinder spindle from a source not shown in the drawings. Said belt is so disposed as to be under the desired driving 90 tension when the transverse member 5 is in its operative position, as shown in Figs. 1 and 3 of the drawings.

The bed-plate 2 carries a vertically disposed cylindrical journal bearing member 100 23, Fig. 3 of the drawings, in the lower portion of which is rotatably carried a spindle 24, having on its lower end a bevel gear 25, the latter being adapted to mesh with, and be driven by a similar gear 26, carried by the 105 inner end of a drive shaft 27, journaled in the frame 1 at 28. A pulley 29, is preferably provided upon the outer end of the drive shaft 27, for receiving power from an outside source, not shown in the drawings. 110

The upper end of the spindle 24 is hollow, and is provided with a lineally disposed key-way 30. A shaft 31 is carried within the upper portion of the journal member 23, and is adapted for rotary and axial movement therein. The lower end 32 of said shaft is adapted to fit within the hollow upper end of the spindle 24, and is provided with a key 33, adapted for engagement with the key-way 30 of said spindle, so that rotary motion is transmitted from the spindle 24 to the shaft 31, but said shaft is permitted to have axial movement within the journal member 23 and the upper end of said spindle.

15 The shaft 31 carries a horizontally disposed chuck 34, Figs. 1, 3 and 4 of the drawings, upon which is removably secured, as by means of clamps 35, a die holding plate 36. The die 37, which is to be ground, is 20 shown as resting partially within said die holding plate, and secured thereto by means of a removable annular collar 38. Secured to the underside of the chuck 34 is a cam member 39, having its lower face adapted to rest 25 upon a roller 40, rotatably carried by a fixed bracket 41, extending upwardly and secured to the bed-plate. The said lower face of the cam 39 is formed with the contour desired for the ground face 42 of the die 37. Therefore, as the chuck 34, carrying said die, is 30 rotated by the described mechanism, said chuck will be moved axially by the action of the cam 39 and its roller 40 to produce upon the face of the die a contour of the desired form.

It will be readily understood that the transverse member 5, carrying the grinder-head, may be elevated as shown in Fig. 4 of the drawings, to permit the die to be placed 40 upon the chuck and removed therefrom. Said die having been secured in place, the transverse member 5 is then returned to the position shown in Figs. 1 and 3 of the drawings and the grinder wheel is adjusted to the 45 proper position, laterally and vertically, by means of the hand wheels 11 and 17, respectively. The chuck is then caused to rotate, and the die will be automatically ground to the desired form, as previously described.

50 I am aware that changes of form and construction may be made in the device as herein described and illustrated, without in any way departing from the spirit of the invention, and it is therefore my wish to be understood as claiming the invention as broadly as the state of the art will permit.

Having thus described the invention, what is claimed as new and desired to be protected 60 by Letters Patent is:—

1. The combination of a rotary work holding chuck axially slidable toward and from the cutting element, a rotary driving spindle therefor slidably connected with said 65 chuck, means for reciprocating said chuck

axially while it is rotating, a rotary cutting element the cutting face of which is presented toward the end of the said chuck at a point distant from the axis of the chuck to operate on the end of an annular die 70 which is secured to the chuck, and power means for rotating said chuck and cutting element together.

2. In a grinding machine, the combination of a vertically and axially movable chuck, 75 means for rotating said chuck, means for moving the chuck axially, a pivoted and movable bar near said chuck, a bearing for a grinding tool, adjusting slides which are respectively vertically movable and horizontally movable, connecting said bearing with said bar, and means for holding the free end of the bar to hold the grinder in operative position, said bar being swingable to remove the grinder from in front of the tool and 80 chuck.

3. A machine for the described purpose comprising grinding means adjustable in two directions, devices for holding the grinding means in fixed position, means for holding the work to be ground, and devices for automatically and constantly rotating and reciprocating said work holding means, to cause the work to be ground to a predetermined form. 95

4. A machine for the described purpose comprising grinding means, devices for holding the grinding means in fixed position, a horizontally rotatable and axially movable chuck constantly operating in connection 100 with said grinding means for continuously holding the work to be ground, mechanism for rotating said chuck, and devices for automatically moving said chuck axially, to cause the work to be ground to a predetermined 105 form.

5. A machine for the described purpose comprising grinding means, devices for holding the grinding means in fixed position, a horizontally rotatable and axially movable 110 chuck adapted to hold the work to be ground, mechanism for rotating said chuck continuously together with said grinding means, a cam carried by said chuck, and a cam follower adapted for co-operation therewith, said cam being adapted to impart axial movement to said chuck during the rotation thereof. 115

6. A machine for the described purpose, comprising grinding means, a horizontally 120 disposed chuck for holding the work to be ground, said chuck being adapted for rotary and axial movement, mechanism for rotating said chuck, an annular cam carried by the under-side of said chuck, and a cam 125 follower upon which said cam is adapted to ride to impart axial movement to said chuck during the rotation thereof.

7. A machine for the described purpose, comprising a rotatable and axially movable 130

5 chuck adapted to hold the work to be ground, mechanism for rotating said chuck, devices for automatically moving said chuck axially during the rotation thereof, grinding means carried in adjustable grinding relation with the work, devices for holding the grinding means in fixed relation to the work during the axial movement of the chuck; and means at will for moving said grinding 10 means away and upward from said chuck to enable the work to be placed thereon and removed therefrom.

15 8. A machine for the described purpose comprising a horizontally disposed bed-plate, a horizontally rotatable and axially movable chuck supported by said bed-plate and adapted to hold the work to be ground, mechanism for rotating said chuck, devices for au-

tomatically moving said chuck axially during the rotation thereof, a pair of fixed brackets extending upwardly from said bed-plate, a transverse member pivotally secured to one of said brackets and removably secured to the other, a grinder-head carried by said transverse member, means for adjusting said grinder-head horizontally and vertically, and grinding means carried by said head in grinding relation with the work.

20 In testimony whereof I have signed my name to this specification in the presence of 25 two subscribing witnesses.
